Term of patent 14 years

Int. Cl. D26—02

U.S. Cl. D48—20

FIG. 1 is a perspective view of a lamp, showing my new design;

FIG. 2 is a front elevational view thereof showing the top of the lamp swiveled to a position 90° from the position shown in FIG. 1; and

FIG. 3 is a plan view of the lamp appearing in FIG. 1. The dominant features of my design reside in the portions shown in full lines in the drawing.

I claim:

The ornamental design for a lamp, substantially as shown and described.
